(57) **CLAIM**

We claim the ornamental design for a pistol, as shown and described.

DESCRIPTION

FIG. 1 is a right side view of an embodiment of a pistol according to the invention;

FIG. 2 is a left side view of the pistol shown in FIG. 1;

FIG. 3 is a front view of the pistol shown in FIG. 1;

FIG. 4 is a rear view of the pistol shown in FIG. 1;

FIG. 5 is a top view of the pistol shown in FIG. 1;

FIG. 6 is a bottom view of the pistol shown in FIG. 1;

FIG. 7 is a right side view of an embodiment of a pistol according to the invention;

FIG. 8 is a left side view of the pistol shown in FIG. 8;

FIG. 9 is a front view of the pistol shown in FIG. 8;

FIG. 10 is a rear view of the pistol shown in FIG. 8;

FIG. 11 is a top view of the pistol shown in FIG. 8; and,

FIG. 12 is a bottom view of the pistol shown in FIG. 8.
